UNITED STATES PATENT OFFICE.

LOUIS STEINBERGER, OF NEW YORK, N. Y.

INSULATING DEVICE.

No. 853,743.

Specification of Letters Patent.

Patented May 14, 1907.

Application filed March 29, 1906. Serial No. 308,662.

To all whom it may concern:

Be it known that I, LOUIS STEINBERGER, a citizen of the United States, and a resident of the city of New York, borough of Brooklyn, 5 in the county of Kings and State of New York, have invented a new and Improved Insulating Device, of which the following is a full, clear, and exact description.

My invention relates to insulating devices 10 of the general character used for supporting conductors carrying heavy currents.

Among the several objects of my invention are the following:—1. To provide an insulator pin containing a strengthening member of insulating material completely embedded therein; 2. To increase the mechanical and dielectric strength of this strengthening member. 3. To make certain provision for rendering the insulating pin water-tight at 15 its base; 4. To render a certain region encircling the base of the pin as dry as possible; 5. To provide an improved water-shedding course for conveying moisture away from the pin and cross-arm; 6. To increase the insulating qualities of the pin and its accompanying parts; 7. To provide upon the pin or analogous member a drip edge raised above the cross arm for the purpose of maintaining the latter comparatively dry at the point adjacent to the hole in the cross arm; 8. To provide certain facilities for holding the pin upon the cross-arm and to carry off the water running down the body of the pin to either side and away from the cross arm; 9. To supply certain mechanical details of construction for improving the mechanical strength of the insulating parts and of improving the general efficiency thereof; 10. To provide a novel means for strengthening a member having a longitudinal conformation; 11. To provide a composite strengthening member made up from a plurality of tubular portions; 12. To provide a composite strengthening member made up from a plurality of tubular portions and a solid core portion; and 13. To make certain provision for protecting the insulating pin at its base and for protecting certain portions of the cross arm adjacent to this base from water, snow, etc.

50 One form of my invention is shown in the accompanying drawings forming a part of this specification, in which similar characters of reference indicate corresponding parts in all the figures.

Figure 1 is a front elevation of a cross-arm provided with my improved insulator pin;

Fig. 2 is a plan view of the same; Fig. 3 is a vertical central section, upon the line 3—3 in Fig. 2, looking in the direction of the arrow, and showing the conformity of the water-shedding course and the dry space separating the same from the cross-arm; and Fig. 4 is a central vertical section upon the line 4—4 in Fig. 2, looking in the direction of the arrow and showing further the appearance of the water-shedding course; also showing how this course is elevated above the cross-arm at certain portions and depressed below the upper surface of the cross arm at other portions than those shown in Fig. 3; and Fig. 5 is a section on the line 5—5 in Fig. 4.

The cross-arm is shown at 5, the pin body at 6, and a thread terminating the upper end of the pin body at 7. A weather shield 8 is made of insulating material and is integral 75 with the pin body 6. This weather shield is provided with a trough 9, having depressed portions 10, as indicated more particularly in Figs. 1 and 2. The weather shield 8 is further provided with raised edges 8^a forming 80 the outer boundary of the trough, and with drip surfaces 12^a raised above the cross-arm and separated therefrom by a space 12, as indicated in Fig. 3. This space is practically continued at 13 as indicated in Fig. 4 and is 85 annular. A central solid rod 11, preferably of fiber, dry wood, or other insulating material, is encircled by a plurality of tubes 11^a, 11^b, also of insulating material, preferably fiber, mica or other material having considerable mechanical strength thus forming a composite core which is embedded within the pin body and concentric therewith. The purpose of this member is to confer mechanical strength and also to increase the insulating qualities of the pin body. The materials of which they are made should preferably have different dielectric constants, as this improves the degree of insulation attained.

As to mechanical strength, it may be stated that in nature and art the cylindrical form is the best known for so utilizing a given quantity of material as to confer upon it the greatest effective strength. The pin body is provided with an annular shoulder 12^c which 100 directly engages the upper surface of the cross-arm, and is also provided with a stem 14. Embedded within this stem is a metallic sleeve 15 provided with a slot 16 and with an annular flange 17, this slot and flange serving to anchor the sleeve immovably within the stem 14. The sleeve 15 is embedded within 105

the stem 14 while the latter is in plastic condition. A screw 18 is fitted into the sleeve 15 which is threaded inwardly for the purpose of receiving it. A washer 19 encircles 5 the screw stem 18, and threaded upon this screw stem is a nut 20. To mount the insulating pin in position it is raised above the cross arm, the stem 14 is inserted as indicated in Figs. 3 and 4, the washer 19 is placed in position, and the screw 18 is then screwed into 10 the sleeve 15. The shoulder 12^e is thus drawn down hard upon the upper surface of the cross arm and forms an annular watertight joint therewith. As above explained, 15 around this water-tight joint is a dry space 12 of annular form which still further increases the insulating qualities of the pin. Moisture collecting in the trough 9 is caused 20 to drift tangentially in a lateral direction and downwardly, so as to accumulate at the point 10, when it is discharged so as to miss the cross arm. In this way, even in the severest rain, no water can accumulate upon the cross arm in the immediate vicinity of the 25 shoulder 12^e, the latter being encircled as above explained by an insulating space. It will be noted that the metallic sleeve 15 and the central composite core are completely separated. This improves the dielectric 30 property of the insulating pin.

It will be evident to those skilled in the art that many changes in construction, form and arrangement of the parts may be resorted to without departing from the spirit or scope of 35 my invention. I therefore do not limit myself to the exact form shown, nor to the details of any or all of the parts herein specified. Nor do I limit myself to any particular combination of parts or to the use of any prescribed materials for the insulating materials 40 for the insulating material; however, I generally employ the material known in the art as "electroso."

Having thus described my invention, I 45 claim as new and desire to secure by Letters Patent:—

1. An insulating device, comprising a pin body provided with a stem for entering a cross arm and with a shoulder for forming a 50 water-tight joint with said cross arm, said pin body being further provided with a weather shield integral therewith and having a space intermediate of said shoulder and said weather shield.

2. An insulating device, comprising a pin body provided with a weather shield integral therewith, said weather shield being provided with a trough, means for mounting said pin body on a cross arm and for sustaining said 55 weather shield out of contact with said cross arm, and means for supporting an insulator.

3. An insulating device, comprising a pin

body of insulating material provided with a weather shield integral therewith and having two opposite sides extended in the form of 65 downwardly-projecting members.

4. An insulating device, comprising a core of insulating material, and a body portion of insulating material encircling the same, said body portion being provided with means for 70 supporting an insulator and with means for mounting said body portion.

5. An insulating device, comprising a supporting pin provided with a weather shield having a restricted water course, and means 75 for mounting said pin to a cross arm, said weather shield being disposed above said cross arm and out of contact therewith.

6. An insulating device, comprising a body portion of insulating material, a strengthening core also of insulating material, the said core being enveloped by the body portion, and means for mounting an insulator upon 80 said body portion of insulating material.

7. An insulating pin, comprising a body 85 portion of insulating material provided with a portion for engaging a cross arm or other support, a strengthening member embedded within said pin body, and a fastening member carried by and anchored in the portion 90 for engaging the cross arm.

8. An insulating device, comprising a pin body of insulating material having completely enveloped thereby a strengthening member built up of a plurality of members arranged one within the other.

9. An insulating device, comprising a solid rod of insulating material, a plurality of tubes of insulating material encircling the rod, and a mass of insulating material surrounding said tubes, said mass of insulating material being provided with means for supporting an insulator.

10. An insulating device, comprising a pin body of insulating material having a tube-like member which is surrounded at its sides and ends by the said insulating material.

11. An insulating device, comprising a body portion of insulating material, and a strengthening core also of insulating material, the said core being enveloped by the body portion, the body portion having its lower end in the form of a member for engaging a support, and the said core extending in the said supporting member a portion of the 115 length of the latter.

In testimony whereof I have signed my name to this specification in the presence of two subscribing witnesses.

LOUIS STEINBERGER.
